CABINET FOR PHONOGRAFS

Alexander D. Burt, Haddon Heights, N. J., assignor to Radio Corporation of America, a corporation of Delaware

Application June 29, 1940, Serial No. 343,107

11 Claims. (Cl. 274—2)

This invention relates to cabinets for housing sound-reproducing apparatus, and more particularly to an acoustic filter therein for attenuating sounds of certain frequencies reproduced by phonographs housed therein.

The term "phonograph" is usually applied to a system in which a needle follows the undulations in the groove of a record and transforms the undulations into corresponding acoustical or electrical variations. Where, for example, an electrical pickup device is employed in conjunction with the record, the mechanical variations therein due to the motion of the needle are transferred to the mechano-electrical transducer and are transformed into the corresponding electrical variations. The vibration of the various elements of the pickup and the vibration of the record itself due to the interaction between the needle and the record results in the production of very high intensity sounds by direct transformation from mechanical variations into acoustical variations of the air immediately surrounding the pickup. Because of the relatively small sizes of the vibrating elements, most of this energy is confined to the high frequency region, and the conditions under which this sound is generated generally leads to considerable distortion in the sound emanating directly from the pickup and the record. Another objectionable feature found in conventional phonographs of the type under consideration is that the sound of high frequencies due to the mechanical vibration is not in phase with the sound emanating from the loudspeaker connected to the pickup through a suitable amplifier because of the short wave lengths of the higher frequency sounds. Also, sounds emitted directly into the atmosphere as a result of the mechanical vibration of the pickup device and/or record are not necessarily harmonically related to the sound produced by the loudspeaker, nor can their volume be controlled. Thus, when the volume of sound emitted by the loudspeaker is low, that emitted by the pickup and record become even more noticeable and objectionable. For the foregoing reasons, it is desirable to suppress the sound which issues directly from the pickup and record system, and the primary object of my present invention is to provide an improved phonograph cabinet which will accomplish this purpose.

More particularly, it is an object of my present invention to provide, in a cabinet for housing sound-reproducing apparatus such as a phonograph, an acoustic filter which will attenuate sounds emanating directly from the record and

pickup and normally reaching the ear of the listener during operation thereof.

Another object of my present invention is to provide an improved cabinet as aforesaid which is simple in construction, inexpensive to manufacture, and highly efficient in use.

In accordance with my invention, I provide either in the upper ends of the walls constituting the body of the cabinet and against which the cover is adapted to close, or in that portion of the cover itself which overlies the aforementioned wall ends, one or more grooves or slots running lengthwise of the wall edges or running parallel to the periphery of the cover. Preferably, these grooves should extend continuously all around the cabinet, the grooves constituting acoustic capacitances which are in shunt relation to the acoustic inertance provided by the slight space between the walls of the cabinet and the cover when the cover is closed. If desired, the space between the cabinet body and the cover may be filled with a material providing an acoustic resistance, such as felt. In any case, the resulting arrangement provides a low pass acoustic filter which is very effective to attenuate the higher frequencies.

The novel features that I consider characteristic of my invention are set forth with particularity in the appended claims. The invention itself, however, both as to its organization and method of operation, as well as additional objects and advantages thereof, will best be understood from the following description of several embodiments thereof, when read in connection with the accompanying drawing, in which

Figure 1 is a sectional view of a cabinet according to one form of my invention;

Figure 2 is a top elevation of the body portion thereof with the cover removed;

Figure 3 is a fragmentary section of another form of my invention;

Figure 4 is a fragmentary section of still another form of my invention;

Figure 5 is an electrical wiring diagram showing the electrical analogue corresponding to the acoustic system of the modification of my invention shown in Figs. 1, 2 and 3, and

Figure 6 is a similar wiring diagram corresponding to the acoustic system of the modification of my invention shown in Fig. 4.

Referring more particularly to the drawing, wherein similar reference characters designate corresponding parts throughout, I have shown a cabinet having a body portion A comprised of a plurality of interconnected walls 1, 3, 5 and 7,

and a cover B hinged to one of the walls, such as the wall 5, and adapted to overlie the upper ends of the walls when the cover B is in closed relation to the body A. The body A is of hollow construction and is provided with a partition or motor board 8 upon which is mounted a suitable phonograph 9 which includes a sound-reproducing instrumentality, such as an electrical pickup device 11.

Due to manufacturing inaccuracies, warpage in the wood of which the cabinet is made, and other similar causes, there is a small space 13 between the cover and the body in practically all cabinets. This space has been somewhat exaggerated in the drawing by having the cover B rest on the hinge 15 and on a pair of rubber or felt bumpers 17. It is through this space that sounds emanating directly from the pickup device 11 and a record 18 due to the mechanical vibration thereof pass out to the exterior of the cabinet and cause considerable annoyance, especially at the higher frequencies.

In order to overcome this difficulty, I provide one or more grooves or slots 21 in the upper ends of each of the walls of the body A in accordance with the form of my invention shown in Figs. 1 and 2. The slots 21 run along the lengths of the upper edges of the walls and continue all the way around the cabinet, as clearly shown in Fig. 2. Any suitable number of slots may be provided and they may be of any desired width and depth. In any case, the slots 21 are in shunt relation to the small spaces 23 constituting acoustic inertances for the passage of sound waves from within the cabinet and located under the marginal portions of the cover B which overlie the wall edges and between the grooves 21. If the inductances m_1, m_2, m_3 and m_4 correspond to the acoustic inertances of the small spaces 23 just referred to, and c_1, c_2, c_3 correspond to the acoustic capacitances provided by the cavities or grooves 21, then the electrical analogue will be as shown in Fig. 5 wherein it will be noted that the capacitances c_1, c_2, c_3 are in shunt relation to the inertances or inductances m_1, m_2, m_3, m_4 , etc. Thus, the acoustic system of Figs. 1 and 2 constitutes a low pass filter which will pass only the lower frequencies but which will attenuate the higher frequencies.

In the form of my invention shown in Fig. 3, I provide the slots 21 in the marginal portion of the cover B, that is, in the portion thereof which overlaps the body walls. In other respects, the two cabinets are alike, and the operation of the acoustic network in this form of my invention is the same as in that previously described.

If desired, the grooves 21 may be formed both in the ends of the cabinet walls and in the cover B, as shown in Fig. 4. In this case, the two sets of grooves 21 are superposed over each other, the grooves of each superposed pair being aligned with each other and preferably of the same width. Obviously, the width and depth of the slots or grooves 21 may be varied, as well as their number, all of these factors determining the cut-off frequency and degree of attenuation for the filter. If desired, also, the spaces 23 between the body A and the cover B may be filled with a material affording an acoustic resistance, such as the felt 25 shown in Fig. 4. In the latter case, there will be included in each branch a resistance r_1, r_2 , etc., in series with the inertance m_1, m_2 , etc., as shown in Fig. 6.

From the foregoing description, it will be apparent to those skilled in the art that I have

provided a novel cabinet which will suppress the annoying higher frequency sounds commonly associated with phonographs. Although I have shown and described several forms of my invention, it will be apparent to those skilled in the art that many other variations thereof are possible. I, therefore, desire it to be understood that my invention is not to be limited except insofar as is made necessary by the prior art and by the spirit of the appended claims.

I claim as my invention:

1. A cabinet for housing sound-reproducing apparatus comprising a body portion and a cover portion movably associated therewith, said parts having portions thereof in overlapping relation when said cover is closed with respect to said body, and at least certain of said overlapping portions being provided with at least one cavity constituting an acoustic capacitance.

2. A cabinet for housing sound-reproducing apparatus comprising a body portion and a cover movably associated therewith, said parts having portions thereof in overlapping and slightly spaced relation when said cover is closed with respect to said body, the space between said cover and said body permitting the passage of sound waves emanating from said apparatus out to the exterior of the cabinet and constituting an acoustic inertance therefor, and at least certain of said overlapping portions being provided with one or more cavities constituting acoustic capacitances adapted to cooperate with said acoustic inertance to attenuate at least a portion of said sound waves.

3. The invention set forth in claim 2 characterized in that said cavities are arranged in shunt relation to said space.

4. The invention set forth in claim 2 characterized in that the end portion of one of said parts is substantially contiguous to the other of said parts and characterized further in that said cavities are constituted by one or more grooves formed in said end portion and extending longitudinally thereof.

5. A cabinet for housing sound-reproducing apparatus comprising a body part constituted by a plurality of interconnected walls and a cover hinged to one of said walls and adapted to overlie the ends of said walls when in closed relation to said body, the ends of said walls adjacent said cover being provided with one or more grooves extending along the lengths thereof.

6. A cabinet for housing sound-reproducing apparatus comprising a body part constituted by a plurality of interconnected walls and a cover hinged to one of said walls and adapted to overlie the ends of said walls when in closed relation to said body, the portion of said cover which overlies said ends being provided with one or more grooves extending substantially parallel to the periphery of said cover.

7. A cabinet for housing sound-reproducing apparatus comprising a body part constituted by a plurality of interconnected walls and a cover hinged to one of said walls and adapted to overlie the ends of said walls when in closed relation to said body, the ends of said walls adjacent said cover being provided with one or more grooves extending along the lengths thereof, and the portion of said cover which overlies said ends being also provided with one or more grooves extending around said cover in parallel relation to said first-named grooves.

8. The invention set forth in claim 7 characterized in that the grooves in said wall ends and

the grooves in said cover are arranged in aligned relation.

9. The invention set forth in claim 7 characterized in that the grooves in said wall ends and the grooves in said cover are arranged in superposed relation, and characterized further in that the pair of grooves of any superposed set of grooves are each of the same width.

10. A cabinet for housing sound-reproducing apparatus comprising a body part and a cover part movably associated therewith, said parts having portions in overlapping relation when said cover is closed with respect to said body and be-

ing slightly spaced from each other, at least certain of said overlapping parts being grooved to provide one or more acoustic capacitances, and means comprising an acoustic resistance substantially filling said space.

11. The invention set forth in claim 7 characterized in that said cover is slightly spaced from said wall ends when in closed relation to said body, and characterized further by the addition of means in said space providing an acoustic resistance.

ALEXANDER D. BURT.
